Primary Examiner — Susan Bennett Hattan*Assistant Examiner* — Suzanne E Tisdell(74) *Attorney, Agent, or Firm* — Richard M. Edge(57) **CLAIM**

The ornamental design for a control enclosure, substantially as shown and described.

DESCRIPTION

FIG. 1 is a perspective view of a control enclosure;

FIG. 2 is a front view thereof;

FIG. 3 is a bottom view thereof;

FIG. 4 is a top view thereof;

FIG. 5 is a back view thereof;

FIG. 6 is a left view thereof;

FIG. 7 is a right view thereof;

FIG. 8 is a perspective view thereof;

FIG. 9 is a perspective view thereof;

FIG. 10 is a perspective view thereof;

FIG. 11 is a perspective view thereof; and,

FIG. 12 is a detailed perspective view of a portion of the control enclosure illustrated in FIG. 1.

The portions of the drawings shown in broken lines form no part of the claimed design.
